UNITED STATES PATENT OFFICE.

EDWARD O'MALLEY, OF JACKSON, TENNESSEE, ASSIGNOR, BY DIRECT AND MESNE ASSIGNMENTS, TO O'MALLEY-BEARE VALVE COMPANY, OF CHICAGO, ILLINOIS, A CORPORATION OF DELAWARE.

VALVE.

978,930.

Specification of Letters Patent. Patented Dec. 20, 1910.

Application filed April 25, 1910. Serial No. 557,363.

To all whom it may concern:

Be it known that I, EDWARD O'MALLEY, a citizen of the United States, residing at Jackson, in the county of Madison and State 5 of Tennessee, have invented new and useful Improvements in Valves, of which the following is a specification.

This invention relates to improvements in valves, and more particularly to that type 10 of valve known as a reciprocating valve.

It is the object of this invention to provide either the head or the seat of the valve, or both members, with removable wearing surfaces, and it is the further object of this 15 invention to make these removable wearing surfaces of such form and thickness that the maximum economy of metal is accomplished in their construction, so that when one of the removable surfaces becomes worn or damaged 20 it may be removed and discarded with but little expense to the user.

The advantages of such an invention are obvious. At the present time a great many valve heads and valve seats are either 25 formed integrally with the respective parts, or if they are removable they are of such dimension that great waste would be incurred if they should be discarded, and for this reason in most cases they are reground 30 or refaced which necessitates the removal of the damaged part, the employment of particular machinery for the refacing or regrinding of the part and then the replacing of the part, while during all of this time the 35 valve is incapable of operation.

This invention comprises a removable part in which but little metal is used, so that when it becomes worn it may be removed and discarded without the use of 40 special tools and a new member be immediately replaced, and the parts placed in working order with but little delay to the operation of the valve. It is also a part of this invention to apply a plurality of these 45 removable parts in nest form, so that when the outermost one becomes worn or damaged it may be removed and thereby presenting the one next below, which will provide a new member, so that the function of 50 the parts in the operation of the valve may be continued immediately.

While the preferred form of this invention is illustrated in the accompanying sheets of drawing, yet it is to be understood that 55 minor detail changes may be made without

departing from the scope thereof, and while one means of attaching the removable members is illustrated in this application, it is to be understood that these members may be held in place in the manner described in 60 my prior applications, Serial Nos. 489,202; 494,329; and 531,599, in which removable members are disclosed.

Figure 1 is a longitudinally sectional view illustrating the application of a plurality 65 or nest of removable members to a globe valve with parts of the valve broken away. Fig. 2 is a view in side elevation of a plurality or nest of removable members. Fig. 3 is a top plan view of the construction in 70 Fig. 2. Fig. 4 is a detail view partly in section illustrating the application of a single removable member to the head of a reciprocating valve. Fig. 5 is a detail view in cross section illustrating the application of a 75 single removable member to a valve seat. Fig. 6 is a top plan view of the construction in Fig. 5. Fig. 7 is a view in end elevation of a single removable member to be applied to a valve seat. Fig. 8 is a top plan view of 80 the construction in Fig. 7.

In Fig. 1, the removable members are shown in nest form secured to the head and seat of the usual form of globe valves. In this case the plurality or nests of removable 85 members as secured to the seat may be termed seat plates, and are held in place upon the integral seat of the valve. The removable members as secured in place upon the head are also in nest form and may be 90 termed head plates. As is customary in valves of this type, the seat is in the form of a ring 1 extending upward from the bridge or web of the valve. The nest of removable seat plates comprises a plurality of very 95 thin plates 2 corresponding in size to the contour of the valve seat, and are secured in place thereon by a securing ring 3 having an inturned flange 4 adapted to engage the uppermost plate. The exterior of the 100 upper projecting seat member 1 is screw threaded and the interior of the securing ring 3 is correspondingly screw threaded to engage therewith.

The valve head 5 as illustrated in this 105 Fig. 1 is of the ordinary type employed in valves of this character in which the head proper is rotatively carried upon the valve stem 6, so that as the head plate is being seated, the head proper will remain sta- 110

tionary in engagement with the seat as the stem is being rotated at the closing of the valve. To accomplish this the end of the valve stem is provided with an outstanding 5 flange or disk 7 of greater diameter than the stem proper. The valve head 5 is provided with an aperture to receive the enlarged head of the stem and the inner walls of this aperture are screw threaded to receive 10 a similarly screw threaded nut 8, which will when secured in place allow of the rotation of the valve stem within the valve head. The valve head on the under side is provided with an enlarged depending screw threaded 15 member 9 and a flat surface 10 upon which the nest of head plates 11 is secured by the securing nut 12 upon the enlarged depending member 9.

In employing a nest of plates it is preferable 20 that the plates be secured in alinement with each other by wiping the edges thereof with solder. In case it is desirable to use but a single removable seat plate in connection with the ordinary valve head in which 25 the valve head is rigidly mounted upon the valve stem provision is made whereby the seat plate may rotate upon the stationary seat member, as the valve is closed and while the head is in contact with the seat plate. 30 To accomplish this the screw threaded portion of the securing ring 3 between the in-turned flange 4 and the bottom of the ring is slightly greater than the thickness of a single plate and the distance between the 35 plate receiving surface upon the seat and where the screw threaded outer portion of the seat member engages the web, so that when the securing ring is advanced as far as possible there will be sufficient play between 40 the inturned securing flange of the ring and the seat plate to allow the seat plate to turn upon the seat member.

When it is desired to apply a single removable head plate to a head of the character 45 illustrated in Fig. 1, and the valve seat is of the ordinary construction, the valve head 5 is provided with a recess 13 between the central depending screw threaded member 9 and the flat portion 10 of the valve head 50 adapted to receive the head plate. The securing nut 12 is provided with a reduced portion 14 adapted to enter into the recessed portion of the valve head, and the outstanding flange or plate engaging member 55 15 of the nut is so constructed in relation to the reduced portion that when the nut is completely seated and the reduced portion is in engagement with the bottom of the recessed portion of the valve head, the 60 head plate will have sufficient play between the securing nut and the valve head to allow it to rotate thereon as the head advances downward and comes into engagement with the valve seat as the valve is being closed.

Fig. 4 illustrates a valve head in which

the head 16 is rigidly secured to the valve stem 17, and the under side of the valve head presents a continuous flat surface 18 from the circumference thereof to the enlarged central screw threaded depending member 70 19. In this case the securing nut 20 is provided with an outstanding securing flange 21 adapted to engage the head plate 22 and the side of the flange in proximity to the head is recessed sufficiently to allow of a 75 play of the head plate between the securing portion of the nut and the head, for the purposes above described.

Figs. 5 and 6 illustrate the application of a single removable seat plate 23 as applied 80 to a valve seat in which a valve head of the ordinary type is employed. In this case the seat member 24 presents a flat surface for engagement with the removable seat plate, and the seat plate is slightly less in diameter 85 than the seat member. The exterior of the seat member is screw threaded and is adapted to engage with the inner screw threaded portion of a securing ring 25. The securing ring is provided with a plurality of spaced 90 apart inwardly projecting members 26 which are shouldered to engage the upper surface of the seat member when the securing ring is in place. The inner side of these members which engage the seat plate are recessed sufficiently to allow of a rotary movement of the seat plates upon the seat member when the valve head comes in contact with the seat plate in the closing movement of the valve. 100

The removable plates for both the heads and seats of valves, as shown and described, are so constructed as to contain the minimum amount of metal in each plate for the purpose specified. In both forms the plates are 105 circular having a central circular cut out portion, so that the width of the metal forming the plates is just sufficient to be engaged by the other operating member of the valve and allow for the securing means which attaches 110 the plate in place to its respective valve member. By this construction a great deal of metal is saved in the manufacture of the plates. The plates are preferably made from relatively hard metal, so that they will 115 have sufficient body when secured in position to accomplish their function, and at the same time increase their duration. Such metal as nickel, brass, phosphor bronze, or similar hard tough metals answer the requirements 120 and will produce a plate that will last approximately as long, without removing or changing, as the ordinary stationary valve or seat members. As these plates will remain in good operative condition approximately 125 as long, the operation of the valve need not be interfered with, for the removal or change of plates, more often than in the case of valves supplied with the ordinary stationary heads and seats and the commer- 130 135

cial value of such a construction is therefore evident. To construct these plates so that a worn or scored plate may be discarded without a loss to the owner and make the application of this invention not only practical, but a great saving to the user, these plates are made extremely thin. In regrinding or refacing a valve head or valve seat, either of the removable or stationary form, a certain amount of metal must be removed in this process from the respective member, in order to cut below the scored or damaged portion and present a perfectly trued surface, and the metal thus removed not only shortens the duration of usefulness of this operative part, but is a total loss to the owner.

The plates constructed in conformity to this invention are preferably only of that thickness which would correspond to the amount of metal removed in the refacing or resurfacing of the corresponding member in valves heretofore used. It will therefore be seen that by the use of the plates of this invention, the discarding of a worn or scored plate not only saves time and expense of refacing or resurfacing the corresponding member, but the worn or scored plates may be discarded without loss to the owner of the valve and without shortening the operative life of the parts thereof. By constructing and securing the plates in the manner described a great saving of material is obtained, not only on account of the thinness of the plates, but on account of their contour.

These plates may be stamped directly from sheets of metal, whose surfaces have been previously trued, or they may be made in any other desirable manner and in any case the metal not actually forming a part of the plate may be remelted and used in the making of other plates.

What I claim is:

1. A removable wearing surface plate of hard metal for the contacting parts of valves

similar in form to the contacting part and of the thickness of the depth of metal removed in grinding and refacing a worn contacting part corresponding thereto.

2. A removable thin flat wearing surface plate of hard metal for the contacting parts of valves similar in form to the contacting part, and of the thickness of the depth of the metal removed in grinding and refacing a corresponding contacting part worn by continual operation of the valve.

3. In a valve including contacting head and seat members, a thin wearing surface plate and means for removably and rotatably securing the plate upon one of the members.

4. Wearing surface plates of hard metal for the contacting parts of valves similar in form to the contacting parts and of the thickness of the depth of metal removed in grinding and refacing a worn contacting part corresponding thereto, in combination with means for removably securing the plates to one of the contacting parts, said means engaging the plate at the edge of the portion of actual contact.

5. In a valve having contacting parts, a wearing surface plate for the contacting parts similar in form thereto and of the thickness of the depth of metal removed in grinding and refacing a worn contacting part corresponding thereto, and means for removably and rotatably securing the plate to one of the contacting parts, said means engaging the plate at an edge of the portion of actual contact.

6. In a valve including a valve head and seat member, a thin wearing surface plate of hard metal for the contacting parts, and means for removably and rotatably securing the plate to one of the contacting parts.

EDWARD O'MALLEY.
